HEEL

Horatio S. Lyness, Lynn, Mass., assignor to
United Shoe Machinery Corporation, Flemington, N.J.

Application October 5, 1939; Serial No. 298,067

3 Claims. (Cl. 36—34)

This invention relates to covered wood heels which have the peripheral portions of their attaching faces in direct contact with the counter portions of uppers of shoes to which they are attached.

In the manufacture of women's shoes having wood heels, for example, it is desirable that the entire rim of the attaching face of the heel, which rim lies in a plane, shall snugly engage the counter portion of the shoe, thereby forming a closed joint between the heel and said counter portion. Because of defects in workmanship it frequently happens that the portion of the shoe counter to be engaged by the heel does not lie in a plane, with the result that open gaps are sometimes formed between the counter portion of the finished shoe and the attached heel of the shoe.

With the above considerations in view it is sometimes the practice to mold the fitted heel seat of the shoe to a predetermined shape by the use of a heel-seat-forming machine and/or to "awl-up" low portions of the heel seat just prior to attaching the heel to the shoe. The above corrective operations increase the cost of the shoe and do not always permanently eliminate the formation of the above-mentioned open gaps between the counter portion of the finished shoe and the heel of the shoe.

In order to insure that the entire rim of the attaching face of the heel shall snugly engage the counter portion of the shoe there is provided, in accordance with a feature of the present invention, a heel having a thin strip of resilient, conformable material such, for example, as relatively firm rubber, interposed between the margin of the attaching face of the heel and a margin of a heel cover inturned upon and secured to said attaching face, said strip extending to but not substantially beyond the rim of said attaching face.

During the heel-attaching operation the strip of rubber is compressed as the margin of the attaching face is forced against high areas of the overlasted counter portion of the shoe, thereby enabling the margin of the attaching face of the heel to be forced against the low areas of the overlasted counter portion of the shoe. When the heel is forced against the fitted heel seat of the shoe, the rubber strip, which is confined between the attaching face of the heel and the cover margin inturned upon and secured to said attaching face, is compressed, causing the inturned cover margin in the vicinity of the rim of the attaching face of the heel to flow toward and into close proximity to the break line of the counter

portion of the shoe, with the result that a closed joint of neat appearance is formed between the entire counter portion and the attached heel of the shoe. The heel engages substantially the entire overlasted counter portion of the shoe which, together with a heel-seat tab formed on the attached sole of the shoe, provides a suitable base to which the heel may be effectively attached. By providing the above heel it has been found that the common tendency of wood heels to break under the pressure applied during the heel-attaching operation has been practically eliminated.

The various features of the invention will be understood and appreciated from the following detailed description read in connection with the accompanying drawing, in which—

Fig. 1 is a perspective view of an illustrative heel a portion of the covering of which has been broken away;

Fig. 2 is a perspective view of the rear end of a shoe to which the heel of Fig. 1 has been applied, the heel seat of the shoe being shown in dotted lines;

Fig. 3 is a section on plane III—III of Fig. 2;

Fig. 4 is an enlarged view showing in section a marginal portion of the heel of Fig. 1 after it has been positioned upon the shoe but before it has been forced with attaching pressure against the heel seat of the shoe;

Fig. 5 is a view similar to Fig. 4 but showing the heel after it has been attached to the shoe;

Fig. 6 is a view corresponding to Fig. 4 but showing in section the marginal portion of a slightly modified heel which is positioned upon the heel seat of the shoe preparatory to its attachment to the shoe; and

Fig. 7 is a view of the heel and shoe illustrated in Fig. 6 after the heel has been attached to the shoe.

The illustrative covered wood heels 20 (Figs. 1 to 5, inclusive), 22 (Figs. 6 and 7), are described with reference to their attachment to the prepared heel seat 24 (Fig. 2) of a shoe 26. In accordance with common practice the heel-seat portion of an attached sole 28 of the shoe 26 is reduced to provide a heel-seat tab 30 (Figs. 2 and 3) which serves as a base to which the heel 20 or 22 may be permanently attached by nails 32 (Fig. 3) and/or by a screw 34 driven through the heel seat 24 and into the heel from the inside of the shoe.

In order to insure against the formation of the above-mentioned gaps between the counter portion of the finished shoe and the rim of the

attaching face of the covered heel of the shoe, the illustrative heel 20 has a U-shaped strip or rand 36 approximately $\frac{1}{2}$ of an inch thick and $\frac{3}{8}$ of an inch wide made of relatively firm but conformable rubber, for example, secured to the margin of its attaching face 38, said strip extending to but not substantially beyond the rim of the attaching face.

In applying a cover 40 to the rigid wood heel the skived top projecting margin 42 of the cover is inturned upon and adhesively secured to the strip 36 and to the attaching face 38 of the heel. In accordance with the usual procedure the forward and lower projecting margins of the cover are inturned upon and secured to the breast and the top-lift-receiving faces, respectively, of the heel. A top lift 44 is later nailed or otherwise secured to the heel.

Fig. 4 illustrates the relative positions of the covered heel 20 and the shoe 26 after the heel has been positioned upon the heel seat 24 of the shoe but before the heel has been forced with attaching pressure against said heel seat. It will be noted that at this stage of the heel-attaching operation a gap 46 is formed between the heel and the break line 48 of the overlasted counter portion of the shoe. When the heel 20 is forced with attaching pressure against the heel seat 24 of the shoe (Figs. 3 and 5), the rubber strip 36 confined between the attaching face 38 of the heel and the inturned margin 42 of the cover is compressed, causing the resiliently backed-up cover margin to flow into voids 52 formed between the heel and the heel seat of the shoe and also to flow toward the break line 48 of the counter portion of the shoe. By interposing the strip 36 of relatively firm but conformable material between the attaching face 38 of the heel and the inturned cover margin 42 it has been found that during the heel-attaching operation the heel cover is moved outward into approximate engagement with the break line 48 of the counter portion of the shoe so as to form between the counter portion and the heel a closed joint 54 (Figs. 3 and 5), the outside surface of the covered heel of the finished shoe being practically continuous with the outside surface of the counter portion of the shoe.

It frequently happens, during the attachment of covered wood heels of the conventional type to shoes, that the heel is broken along the rim of its attaching face. When the heel 20 is forced against the heel-seat portion 24 of the shoe 26 it has been found that the rubber strip 36 cushions and distributes the pressure of the heel against the heel seat with the result that such a heel is almost never broken during its attachment to the shoe.

The heel 22 shown in Figs. 6 and 7 has a shallow U-shaped rabbet 56 formed in the margin of its attaching face 58, and adhesively secured in the rabbet is a U-shaped strip 60 of relatively firm but conformable material. The strip 60 projects slightly above an adjacent portion of

the attaching face 58 of the wood heel 22 and terminates a short distance from a shoulder 62 (Fig. 6) of the rabbet 56. Applied to the heel 22 is a cover 64 the beveled projecting portion 66 of which is inturned upon and secured to the strip 60 and to the attaching face 58 of the heel. As the heel 22 is forced against the heel seat 24 of the shoe the outer portion of the strip 60 confined between the attaching face 58 of the heel and the inturned cover margin 66 is compressed, causing a small bead 68 (Fig. 7) of the cover margin 66 backed up by the strip 60 to be moved into approximate engagement with the break line 48 of the overlasted counter portion of the shoe, thereby forming between the counter portion of the shoe and its attached heel a closed joint 70 which is of neat appearance.

Having described the invention, what I claim as new and desire to secure by Letters Patent of the United States is:

1. A rigid heel having secured to its rear and side faces a cover a margin of which is inturned upon and secured to the attaching face of the heel, said heel having a thin strip of resilient conformable material interposed between the margin of its attaching face and a portion of the inturned cover margin, said strip extending to but not substantially beyond the rim of said attaching face and being adapted to force, during the attachment of the heel to a shoe, the cover of the heel outwardly toward a break line of the counter of the shoe thereby closing any open gap which otherwise would appear between the counter portion of the finished shoe and its attached heel.

2. A rigid heel having in the rear and side margins of its attaching face a shallow rabbet, and a thin strip of resilient conformable material which is arranged in the rabbet and extends to but not substantially beyond the rim of said attaching face, said heel having secured to its rear and side faces a cover a margin of which is inturned upon and secured to said strip of conformable material and to the attaching face of the heel, said strip being adapted to force, during the attachment of the heel to a shoe, the cover of the heel outwardly toward a break line of the counter of the shoe thereby closing any open gap which otherwise would appear between the counter portion of the finished shoe and its attached heel.

3. A rigid heel having in the rear and side margins of its attaching face a shallow U-shaped rabbet, and a thin U-shaped strip of resilient conformable material which is arranged in the rabbet and which projects above the attaching face of the heel and extends to but not substantially beyond the rim of said attaching face, said heel having secured to its rear and side faces a cover a margin of which is inturned upon and secured to said strip of conformable material and to the attaching face of the heel.

HORATIO S. LYNESS.
